BATON HAVING SELECTIVELY
ILLUMINATED SECTION

John W. Peters, Cincinnati, Ohio

Application June 25, 1948, Serial No. 35,231

1 Claim. (Cl. 240—6.42)

1

This invention relates to an illuminated baton, wand, or the like.

An object of the invention is to provide a baton or the like with illuminating means capable of transposition within the baton to produce various desirable lighting effects.

Another object is to provide an illuminated device of the character stated which utilizes lighting means in unitary or cartridge-like form, to facilitate and expedite replacements at low cost, and with little effort requiring no mechanical skill.

A further object is to provide an illuminated baton which is durable, relatively inexpensive, safe to use, and simple in construction and operation.

Another object of the invention is to provide an illuminated baton depending for its selective lighting effects upon standard and readily available flash-light units which are simple and inexpensive.

Another object is to enhance the brilliancy of lighting in an illuminated baton.

The foregoing and other objects are attained by the means described herein and illustrated upon the accompanying drawings, in which:

Fig. 1 is a side elevational view of the improved baton incorporating the present invention.

Fig. 2 is a perspective view of a lighting unit used in the baton.

Fig. 3 is a perspective view of a head or end-piece for the baton.

Fig. 4 is a fragmental cross-sectional view of one end of the baton shaft, showing the lighting units arranged for illuminating the head only of the baton, the head being removed in this view.

Fig. 5 is a view similar to Fig. 4, on an enlarged scale, showing disposition of the lighting units for illuminating both the head and the translucent shaft, the head being removed.

With reference to the accompanying drawing, the baton of this invention comprises generally an elongate straight shaft 8 having fixed to its opposite ends 9 and 10 the hollow sleeves 12, each of which sleeves contains a pair of lighting units 13, one of which is illustrated by Fig. 2. At the free ends 14 of the sleeves are applied suitable end pieces for closing or capping the ends of the sleeves, one of which end pieces may be in the form of a sphere or knob 15, whereas the other may be in the form of an elongate plug or extension 16. The parts 8, 15 and 16 may be formed of a glass-like substance, for example translucent plastic composition capable of trans-

2

mitting light. As shown, these translucent parts are of solid translucent plastic material, and each has its outer surface ground, pitted, or otherwise roughened for the purpose of refracting light rays projected lengthwise therethrough thereby to render the parts brilliantly radiant when light rays are projected therethrough as stated. It is to be understood that parts 8, 15 and 16, or any of them, might be made hollow if desired, with either the interior surface or the exterior surface thereof roughened for refracting the light rays projected into them by the lighting units 13.

The lighting units, as illustrated, are commonly procurable upon the market and are inexpensive standard items of manufacture. Each comprises an elongate casing, usually of metal, having a forward end 17 which is open at 18 and houses an electric lamp 19 which preferably is protected by the rim of the opening. At the rear end 20 of the casing is an extending push-button 21 to be depressed inwardly for closing an electric switch built within the casing. The switch is of the momentary contact type, and is normally open-circuited, so that pressure axially applied to the push-button is necessary in order to close the switch and to energize the lamp 19. The casing of the lighting unit carries one or two dry cells 40, and a spring for normally holding the push-button 21 in the outwardly extended position. Lighting units of the character above described are very common articles of manufacture, and for that reason no attempt is made here to detail the construction thereof.

In Fig. 1 the lighting units are shown arranged to project light rays toward and into the opposite ends 9 and 10 of the translucent shaft 8. The endmost lighting units shown in Fig. 1 have their lamps 19 directed outwardly in opposite directions, to project light rays into the translucent end pieces or heads 15 and 16 axially thereof. It will be noted also in Fig. 1, that the push-buttons 21 of the lighting units at each end of the baton contact one another, so that by applying inward force to the endmost lighting units, all of the push-buttons will be depressed for closing the switches of the lighting units and energizing their respective lamps 19.

From the foregoing it will be understood that the heads 15 and 16 are to be adjustable lengthwise of the sleeves 12, for selectively applying or releasing endwise pressure upon the lighting units, to either energize or de-energize the several lamps 19. The aforesaid adjustment may be accomplished in various fashions, for ex-

ample in the case of the head 16, the inner reduced end 22 thereof may be exteriorly threaded as shown, to engage corresponding threads 23 within the free end 14 of the sleeve 12, so that the annular free end 24 of the head may bear against the adjacent end of the lighting unit, to drive the lighting unit inwardly when the head is screwed into the sleeve to cause depression of the adjacent lighting units and thereby energize their electric lamps. By partially unscrewing the head 16, pressure upon the push-buttons 21 is relieved, allowing the push-buttons to assume their normal extended condition at which the lighting unit switches are opened for de-energizing the lamps.

In the case of the translucent head 15, the end of the head may be bored as indicated at 25 to provide an interior shoulder 26 adapted to contact the forward end of the adjacent lighting unit 13 and drive it toward the other lighting unit when the head 15 is moved to the right, as by advancing it in that direction along the exterior screw threads 21 of sleeve 12. By partially unscrewing the head 15, pressure upon the lighting units is relieved in order to permit extension of the push-buttons 21 in the manner previously explained.

From the foregoing it will be understood that the operator may effect illumination of the baton in its several translucent parts 8, 15 and 16, by advancing the heads toward one another along the screw threads 21 and 23 until the lighting units are compressed lengthwise to depress their respective push-buttons 21 which energize the lamps of the lighting units. If desired, the illumination at one end of the baton may be effected without illuminating the opposite end thereof, depending upon which one of the heads is manipulated for compressing the lighting units.

Referring now to Fig. 4, it will be noted that the lighting unit 13 closest to the translucent shaft 8 has been reversed so that endwise force applied to the rim 127 would serve to depress the push-button 21 of the endmost lighting unit, to energize its lamp, without depressing the push-button of the innermost unit. This last mentioned push-button, as will be observed, extends freely into a socket 28 formed in one end of the shaft 8 with sufficient clearance to preclude actuation of the push-button irrespective of any force applied at 127. Thus, when a head such as 15 is applied to the end 14 of the device as illustrated by Fig. 4, the outermost lighting unit 13 will be advanced to the right resulting in depressing its push-button 21 and energizing the lamp 19 to illuminate the head. The push-button of the outermost lighting unit may press against the lamp, or against some portion of the forward end of the innermost lighting unit. The push-button of the innermost lighting unit under circumstances illustrated by Fig. 4, will not be depressed and accordingly, the shaft 8 will not be illuminated.

Referring now to Fig. 5, the lighting units 13 are arranged in accordance with the disclosure of Fig. 1, for illuminating the head 15 and the shaft 8, when the head is applied to the maximum point of advancement along the threads 27 of sleeve 12. It will readily be understood that the lighting units may be reversed or arranged in selected fashion at either end of the baton, to obtain various desirable lighting effects. By properly rearranging the lighting units, it is possible to illuminate the shaft 8

only, if desired, or alternatively the heads or either of them may be illuminated with or without illuminating the shaft of the baton.

With further reference to Fig. 1, it may be noted that the head 15 is counterbored as at 29 to receive freely the push-button 21 of the outermost lighting unit in the event that the operator wishes to avoid illumination of the head 15. Similarly, the head 16 at the opposite end of the baton may be counterbored as at 30, for the same purpose.

In Fig. 3 is illustrated a modified form of head 31 which may simulate the head 15, except for the fact that the head 31 may be formed of opaque material such as soft rubber or other composition. If the head 31 is constructed of soft rubber or the like, it may be applied to the threaded end 14 of the baton without the need for internal threads within the bore 32. The modified form of head may be provided with a counterbore or socket 33 similar to that indicated at 9 of Fig. 1 to loosely receive the push-button of an endmost lighting unit. The shoulder 34 will serve then as the means for contacting and driving inwardly the rear end 20 of a lighting unit, causing depression of the push-button of an adjacent lighting unit which may function to illuminate the translucent shaft 8. As previously stated herein, the push-buttons 21 may bear against either the lamp or the forward end of the casing of an adjacent lighting unit, as suggested by the disclosure of Fig. 4.

Access to the lighting units may be gained by removing the heads 15 and 16, or if desired, the device may be constructed in accordance with Fig. 5 wherein the sleeve 12 is detachably threaded at 35 to an end of the shaft 8, for rendering the lighting units accessible for removal or replacement. It is to be understood that the various detachable connecting means at the locations 35, 21, 23 and 9 may be of any customary or acceptable form, the threaded connections illustrated being by way of example only. In practice, the connection made at 9 may be simply a pressed fit, or one in which pins, rivets, slip-rings or interfitting flanges might be employed, to mention a few of the ordinary methods of attachment.

It may be considered desirable, in forming the casings of the lighting units, to make the forward openings 18 sufficiently small in diameter to provide seats for the push-buttons of adjacent units, thereby to avoid the application of any compressive force directly to the lamp; or in some cases the forward opening of each lighting unit might be provided with a suitable guard for the same purpose. It may be stated, however, that lighting units are available in which the lamps are very durable and will withstand any ordinary force that might be applied thereto by an adjacent push-button even though the baton may be dropped upon a hard surface or otherwise subjected to shock or mistreatment.

As was previously stated herein, the various translucent parts such as 8, 15 and 16 might be made tubular or hollow rather than solid, if desired. For example, if the shaft 8 of Fig. 5 were made tubular in form, the bore 28 might extend throughout the length of the shaft, and have its interior wall suitably roughened, pitted, or etched, for refracting light rays from the lamp 19, thereby to induce maximum luminosity of the translucent shaft 8. Substantially the same results are obtained by similarly treating the exterior surface of shaft 8 along its entire length.

It is to be understood that various other modifications and changes in the structural details of the device may be made within the scope of the appended claim, without departing from the spirit of the invention.

What is claimed is:

An illuminated baton which comprises a shaft of translucent material, a pair of cylindrical sleeves each having an end fixed upon an end of the shaft with free ends of the sleeves extending from and in alignment with the ends of the shaft, a pair of battery operated lighting units in each of the sleeves, each of said units comprising a cylindrical case disposed in the sleeve, a lamp at one end of each case, a switch button extending from the opposite end of the case, a battery in the case between the lamp and the switch button, electrical connections from the battery to the lamp to cause illumination of the lamp when the switch button is depressed, and spring means urging the switch button to light extinguished position when released, the lighting units of each pair having switch buttons in engagement so that the units are illuminated and shut off when advanced lengthwise toward and away from each other, and a pair of baton heads, each of said heads being formed of translucent material and being threadably attached to

- a free end of one of the sleeves and having a bearing surface engaging an outer unit of one of the pairs of units to advance the units of the pair toward each other when the head is turned in one direction, the units being released when the head is turned in the other direction, whereby the shaft and the heads are illuminatable by the units and the units may be lighted and extinguished by turning the heads of the baton, 10 the ends of the shaft of the baton and the heads of the baton being provided with wells, the lighting units being reversible in the sleeves to dispose the switch buttons thereof in said wells, whereby at least one of the units may be maintained extinguished while other units are illuminated.
